UNITED STATES PATENT OFFICE.

CYRUS S. OLDRYD, OF CINCINNATI, OHIO, ASSIGNOR TO OLDRYD MANUFACTURING COMPANY, OF KNOXVILLE, TENNESSEE, A CORPORATION OF TENNESSEE.

MINING AND QUARRYING MACHINE.

Application filed June 3, 1919, Serial No. 301,478. Renewed December 11, 1922.

To all whom it may concern:

Be it known that I, CYRUS S. OLDRYD, a citizen of the United States, residing at Cincinnati, in the county of Hamilton and 5 State of Ohio, have invented a new and useful Improvement in Mining and Quarrying Machines, of which the following is a specification, reference being had to the accompanying drawing.

10 My improvement relates particularly to machines used for cutting into upright walls of coal, rock, or similar material, the machine comprising cutting means actuated by the machine and projected endwise into 15 the wall of coal, or other material, and then moved sidewise to make a sweeping cut; the machine being, however, adapted to cut in a variety of other ways.

The object of my present improvement is 20 to embody in such a machine efficient means for propelling the machine.

By way of general statement, it may be said that the machine to which this invention relates consists of (1) a truck having a 25 rigid frame or body and having supporting or traction wheels adapted to rest on ordinary rail tracks or on a floor; (2) a neck located at the front of the truck body and rotatable on a horizontal axis extending 30 lengthwise of the machine and approximately in an upright plane cutting midway between the track rails; (3) and cutting mechanism supported by said neck and adapted to be adjusted for cutting in various directions. The improvement of this application relates only to the truck and to the mechanism whereby power is transmitted 35 from a motor supported by the truck to the truck supporting wheels, whereby the truck 40 is propelled in either direction at such relatively high speed as is desirable for moving the machine when the cutting mechanism is not in operation and also mechanism under the control of the operator for applying 45 power from the truck motor to the truck carrying wheels for imparting such slow progression to the truck as is desirable when the cutting mechanism is cutting.

For such cutting mechanism as has been 50 above indicated, reference is here made to my application for Letters Patent of the United States, Serial Number 166,172, filed May 3, 1917, for an improvement in mining and quarrying machines. The machine of 55 said application embodies a truck and pro-

pelling mechanism which differ in various particulars from the truck and propelling mechanism of this application.

In the accompanying drawings,

Fig. 1 is an elevation of the right hand 60 side of a machine embodying my improvement, the cutting mechanism being shown the same as in my said application Serial Number 166,172;

Fig. 2 is a plan of the same machine, a 65 part of the cutting mechanism being omitted and a part of the cover being broken away;

Figs. 3^a and 3^b together show an upright 70 section on the middle longitudinal line of Fig. 2, Fig. 3^a showing the rear part and Fig. 3^b the forward part of the machine, the cutting mechanism being omitted;

Fig. 4 is an upright, transverse section on the line 4—4, of Fig. 6, looking toward the 75 left, parts being broken away;

Fig. 5 is a horizontal section on the line, 5—5, of Fig. 4;

Fig. 6 is a plan of the machine, drawn to a larger scale and some parts being omitted and others broken away;

Fig. 7 is an upright section on the line, 7—7, of Figs. 4 and 6, looking in the direction of the arrow, parts being broken away;

Fig. 8 is a plan of the mechanism shown 80 by Fig. 7;

Fig. 9 is a horizontal section on the line, 9—9, of Fig. 4.

Referring to said drawings, A¹⁰, are four track wheels resting on track rails, R. Said wheels are arranged in pairs on two horizontal axles, A⁸. Each of said axles rests in bearings, A⁹, formed on the lower part of the body, A, of the machine. Said body has a floor or bed, A¹, and a right hand upright wall, A², and a left hand upright wall, A³, 95 and a rear cross wall, A⁶, and a front cross wall, A⁷.

Immediately at the rear of the rear cross wall, A⁶, is an electric motor, M, having a shaft, M¹, from which power is to be transmitted to the axles, A⁸.

In the front cross wall, A⁷, on the axial line of the motor, is a bearing, D¹, in which rests a neck, D, which supports the cutting mechanism. Said bearing is formed by cutting out the upper edge of the cross wall, A⁷, and the lower edge of a bearing block, D², which rests upon the upper edge of the wall, A⁷, and between the side walls, A² and A³.

The rear end of the neck projects through said bearing and is there surrounded by a worm gear wheel, D³, which bears against the rear face of said cross wall. By this means the forward movement of said neck is prevented. Immediately at the rear of the worm wheel is a friction clutch member, D⁶, which has a sleeve, D⁷, extending forward into the neck. A neck shaft, D⁴, lying within the neck extends rearward into the forward portion of said sleeve and is keyed to the sleeve, so that said clutch member and said sleeve and said shaft must rotate in unison. At the rear of the neck shaft, the sleeve, D⁷, receives and forms a bearing for the forward end of the main transmission shaft, B, which is joined to the motor shaft, M¹, by means of a coupling, M².

The function of the neck shaft is to transmit power to the cutting mechanism as described in my said application Serial Number 166,172. Rotation is imparted to the worm wheel, D³, and the neck, D, by the mechanism described in my above-mentioned application.

On the main transmission shaft, B, is a spiral gear wheel, B¹, which meshes with a spiral gear wheel, B², which is loose on the upright shaft, B⁴, which rests in bearings, B⁵ and B⁶. On the bearing, B⁵, rests the lower end of a spacing sleeve, B⁷, which surrounds the shaft, B⁴, and supports a bevel gear wheel, B⁸, which is cast integral with the spiral gear wheel, B². The bevel gear wheel, B⁸, meshes with the bevel gear wheel, B⁹, which is fixed on a shaft, B¹⁰, resting in a bearing, B¹¹, and extending through the side wall, A². On the outer end of said shaft is fixed a crank, B¹², to which is coupled the lower end of a pitman, B¹³. The upper end of said pitman is coupled to a rocking member, B¹⁴, which is hinged on the horizontal shaft, B¹⁴. On said shaft is fixed a ratchet wheel, B¹⁶, and on the rocking member is a reversible pawl, B¹⁵, which engages the teeth of the ratchet wheel. A slide member, B¹⁷, is pressed by a spring, B¹⁸, toward the pawl and thus controls the pawl. On the shaft, B¹⁴, is a gear worm, B¹⁹, which meshes with a worm wheel, B²⁰, which loosely surrounds the shaft, B⁴, below the bearing, B⁶.

From the spiral gear wheel, B¹, the spiral gear wheel, B², receives constant rotation, and through the bevel gear wheels B³ and B⁸, and the shaft, B⁹, and the crank, B¹², and the pitman, B¹³, and the ratchet wheel, B¹⁶, and a shaft, B¹⁴, and the worm, B¹⁹, the worm wheel, B²⁰, receive constant rotation.

But since the wheel, B², and the wheel, B²⁰, are loose on the shaft, B⁴, said shaft does not receive rotation for either of said wheels until connection is made between one of said wheels and the jaw clutch, B²¹, which is feathered on the shaft, B⁴, so as to be slideable endwise on said shaft and so as to com-

pel the rotation of said shaft when the clutch is rotated.

In the upper face of the spiral gear wheel, B², are sockets, B²², adapted to receive the lower jaws of the clutch. On the lower side of the worm wheel, B²⁰, is a jaw clutch member, B²³, which is adapted to be engaged by the upper end of the clutch, B²¹.

At the middle of the clutch, B²¹, is a circumferential groove, B²⁴, in which rests a clutch ring, B²⁵, on which are diametrically oppositely located studs, B²⁶. Each of said studs is engaged by a horizontal fork, B²⁷, which is rigid on a rock-shaft, B²⁸, which is transverse to the length of the machine and rests in bearings, B²⁹, said bearings being applied to the inner faces of the side walls, A² and A³. To the rock-shaft, B²⁸, is attached the upper end of an upright arm, B³⁰, to the lower end of which is coupled the forward end of the horizontal connecting rod, B³¹. The rear end of said rod is coupled to a quadrant lever, B³², which is associated with a quadrant, B³³, which has three notches, B³⁴.

Rocking the shaft, B²⁸, causes the raising and lowering of the clutch, B²¹. Shifting the quadrant lever causes the rocking of the rock-shaft through the action of the connecting rod, B³¹, and the arm, B³⁰. The parts are so proportioned as that when the quadrant lever is set on the middle notch, B³⁴, the clutch, B²¹, is held in neutral position—out of engagement with both the wheel, B², and the wheel, B²⁰—and that when the quadrant lever is set on one of the other notches, the clutch is in engagement with either the wheel, B², or the wheel, B²⁰.

When the clutch is in engagement with the wheel, B², the transmission is directly from the main shaft, B, through the wheel, B², and the clutch to the shaft, B⁴. When the clutch is in engagement with the wheel, B²⁰, the transmission is through the lower course, including the crank, pitman, and ratchet mechanism and the wheel, B²⁰. On this course there is reduction of velocity by the ratchet mechanism and also from the shaft, B¹⁵, by the worm, B¹⁹, to the worm wheel, B²⁰. This transmission is reversed by reversing the pawl, B¹⁵.

This reduced velocity is to be utilized when the machine is cutting. The higher velocity received through the direct transmission is to be used when the machine is to be moved while it is not cutting. When that velocity is used, the direction of travel of the machine is to be reversed by reversing the motor, M. But during the cutting operation the motor must not be reversed. Hence, the mechanism which provides the slow or cutting propulsion of the machine is made reversible.

On the lower end of the upright shaft, B⁴, is fixed a bevel gear wheel, B³⁵, which

meshes with a bevel gear wheel, A^{11} , on the rear axle, A^8 . The wheel, A^{11} , meshes with a bevel gear wheel, A^{12} , on a horizontal shaft, A^{13} , which shaft rests in a bearing, 5 A^{14} , formed in a horizontal bracket, A^{15} , projecting inward from the right hand wall, A^2 , of the body, A , of the machine and in a bearing, A^{16} , in the front cross wall, A^7 . Forward of said bearing a bevel gear wheel, 10 A^{17} , is fixed on the front end of said shaft and meshes with a bevel gear wheel, A^{18} , on the front axle, A^8 . When the shaft, B^4 , is rotated, there is transmission of motion from the bevel wheel, B^{35} , to the bevel gear 15 wheel, A^{11} , and from the latter to the adjacent axle, A^8 , and from the bevel gear, A^{11} , to the bevel gear wheel, A^{12} . From the latter there is transmission of motion through the shaft, A^{13} , and the bevel gear wheels, 20 A^{17} and A^{18} , to the front axle, A^8 . Through the gearing intervening between the two axles, A^8 , said axles are held for movement in unison.

Going from the axle, A^8 , toward the motor, M , the shaft, B^4 , may be regarded as the "first shaft" while the shaft, B , is regarded as the "second shaft." And the transmission shaft, B^9 and B^{14} , may be regarded, respectively, as the "third" and 30 "fourth" shafts.

The mechanism for controlling and varying and reversing the transmission for propulsion is all located above the wheel axles at a convenient elevation within the body 35 of the machine where there is ample space for said mechanism and the mechanism is accessible and protected.

On the rear axle is fixed a brake drum, A^{19} . A brake strap, A^{20} , is applied around 40 said drum. One end of said strap is applied to the front face of the cross wall, A^6 . Thence said strap extends downward beneath the drum, A^{19} , and forward and upward above the drum. To that end is coupled 45 the front end of a horizontal connecting rod, A^{21} . Said rod extends rearward through an aperture, a^{20} , in the strap, A^{20} , and thence rearward to a quadrant lever, A^{22} , which is combined with a quadrant, A^{23} , to permit putting the connecting rod 50 under strain.

I claim as my invention,

1. In a machine of the nature described, the combination of cutting mechanism and 55 a truck supporting the cutting mechanism, the truck comprising carrying wheels, axles on which said carrying wheels are mounted, a first shaft, gearing connecting said shaft with one of said axles, two gear members 60 loosely surrounding the first shaft, a second driven shaft, means for constantly transmitting motion from said second shaft to one of said gear members, means comprising ratchet mechanism for constantly transmitting motion from one of said members

to the other of said gear members, and clutch mechanism slidable on the first shaft for engaging either of said members to compel the rotation of the first shaft, substantially as described. 70

2. In a machine of the nature described, the combination of cutting mechanism and a truck supporting the cutting mechanism, the truck comprising carrying wheels, axles on which said carrying wheels are mounted, a first shaft, gearing connecting said shaft with one of said axles, two gear members loosely surrounding the first shaft, a second driven shaft, means for constantly transmitting motion from said second shaft to one of said members, means comprising ratchet mechanism for constantly transmitting motion from said member to the other of said members, and clutch mechanism located on the first shaft between said members for engaging either of said members to compel rotation of said first shaft, substantially as described. 75

3. In a machine of the nature described, the combination of cutting mechanism and a truck supporting the cutting mechanism, the truck comprising carrying wheels, axles on which said carrying wheels are mounted, a first shaft, gearing connecting said shaft with one of said axles, two gear members 80 loosely surrounding the first shaft and constantly rotating at different velocities, a second shaft, means for transmitting motion from said second shaft to one of the gear members, a third shaft, means for transmitting motion from the second shaft to the third shaft, a fourth shaft, means for transmitting motion from the third shaft to the fourth shaft, means for transmitting motion from the fourth shaft to the second of said 85 gear members, and clutch mechanism for engaging either of said gear members to compel rotation of the first shaft, substantially as described. 90

4. In a machine of the nature described, the combination of cutting mechanism and a truck supporting the cutting mechanism, the truck comprising carrying wheels, axles on which said carrying wheels are mounted, a first shaft, gearing connecting said shaft to one of said axles, a gear member loosely surrounding said shaft, a second shaft, means between said second shaft and said gear member for constantly rotating the latter, a second gear member also loosely surrounding the first shaft for rotation thereon, means between the first gear member and the second gear member for transmitting motion from the first gear member to the second gear member at a different velocity, and clutch mechanism on the first shaft for engaging either of said gear members to compel rotation of said shaft, substantially as described. 100

5. In a machine of the nature described, 110 the combination of cutting mechanism and a truck supporting the cutting mechanism, the truck comprising carrying wheels, axles on which said carrying wheels are mounted, a first shaft, gearing connecting said shaft to one of said axles, a gear member loosely surrounding said shaft, a second shaft, means between said second shaft and said gear member for constantly rotating the latter, a second gear member also loosely surrounding the first shaft for rotation thereon, means between the first gear member and the second gear member for transmitting motion from the first gear member to the second gear member at a different velocity, and clutch mechanism on the first shaft for engaging either of said gear members to compel rotation of said shaft, substantially as described. 120

6. In a machine of the nature described, 125

the combination of cutting mechanism and a truck supporting the cutting mechanism, the truck comprising carrying wheels, axles on which said carrying wheels are mounted, 5 a first shaft, gearing connecting said shaft to one of said axles, a gear member loosely surrounding said shaft, a second shaft, means between said second shaft and said gear member for constantly rotating the latter, 10 a second gear member also surrounding the first shaft for rotation thereon, reversible means between the first gear member and the second gear member for transmitting motion from the first gear member to the second gear member, and clutch mechanism on the first shaft for engaging either of said clutch members to compel rotation of said shaft, substantially as described.

6. In a machine of the nature described, 20 the combination of cutting mechanism and a truck supporting the cutting mechanism, the truck comprising carrying wheels, axles on which said carrying wheels are mounted, a first shaft, gearing connecting said shaft to one of said axles, a gear member loosely surrounding said shaft, a second shaft, means comprising ratchet mechanism between said second shaft and said gear member for constantly rotating the latter, a second gear member also surrounding the first shaft for rotation thereon, means between the first gear member and the second gear member for transmitting motion from the first gear member to the second gear member, and clutch mechanism on the first shaft for engaging either of said clutch members to compel rotation of said shaft, substantially as described.

7. In a machine of the nature described, 40 the combination of cutting mechanism and a truck supporting the cutting mechanism, the truck comprising carrying wheels, axles on which said carrying wheels are mounted, a first shaft, gearing connecting said shaft to one of said axles, a gear member loosely surrounding said shaft, a second shaft, means between said second shaft and said gear member for constantly rotating the latter, a second gear member also surrounding the first shaft for rotation thereon, reversible means between the first gear member and the second gear member for transmitting motion from the first gear member to the second gear member at a different velocity, and clutch mechanism on the first shaft for engaging either of said gear members to compel rotation of said shaft, substantially as described.

8. In a machine of the nature described, 60 the combination of cutting mechanism and a truck supporting the cutting mechanism, the truck comprising carrying wheels, axles on which said carrying wheels are mounted, a first shaft, gearing connecting said shaft with one of said axles, two gear members

loosely surrounding the first shaft, a second driven shaft, means for transmitting motion from said second shaft to one of said members, means comprising two speed reductions for transmitting motion from said member to the other of said members, and clutch mechanism for engaging either of said members to compel the rotation of the first shaft, substantially as described.

9. In a machine of the nature described, 75 the combination of cutting mechanism and a truck supporting the cutting mechanism, the truck comprising carrying wheels, axles on which said carrying wheels are mounted, a first shaft, gearing connecting said shaft with one of said axles, two gear members loosely surrounding the first shaft, a second driven shaft, means for transmitting motion from said second shaft to one of said members, means comprising ratchet mechanism 80 and worm gearing for transmitting motion from said member to the other of said members, and clutch mechanism located between said members for engaging either of said members to compel rotation of said first shaft, substantially as described.

10. In a machine of the nature described, the combination of cutting mechanism and a truck supporting the cutting mechanism, the truck comprising carrying wheels, axles 95 on which said carrying wheels are mounted, a first shaft, gearing connecting said shaft with one of said axles, a main transmission shaft, a neck shaft connected with the main transmission shaft for rotation with the latter, cutting mechanism in operative relation with the neck shaft, two gear members loosely surrounding the first shaft, means for transmitting motion from the main transmission shaft to one of said members, 100 means for transmitting motion from said gear member to the other of said gear members at a different velocity, and clutch mechanism for engaging either of said gear members to compel rotation of said first shaft, substantially as described.

11. In a machine of the nature described, the combination of cutting mechanism and a truck supporting the cutting mechanism, the truck comprising carrying wheels, axles 115 on which said carrying wheels are mounted, a first shaft, gearing connecting said shaft with one of said axles, a second shaft and operator-controlled gearing comprising ratchet mechanism between the second shaft 120 and the first shaft for transmitting motion from the second shaft to the first shaft at different velocities, the direction of the low velocity transmission being reversible, substantially as described.

12. In a machine of the nature described, the combination of cutting mechanism and a truck supporting the cutting mechanism, the truck supporting carrying wheels, axles on which said carrying wheels are mounted, 130

a first shaft, gearing connecting said shaft with one of said axles, two gear members loosely surrounding the first shaft, a second driven shaft, means for transmitting motion 5 from said second shaft to one of said gear members, means comprising reversible ratchet mechanism for transmitting motion from one of said gear members to the other of said members, and clutch mechanism for 10 engaging either of said members to compel the rotation of the first shaft, substantially as described.

13. In a machine of the nature described, the combination of cutting mechanism and 15 a truck supporting the cutting mechanism, the truck comprising carrying wheels, axles on which said carrying wheels are mounted, a first shaft, gearing connecting said shaft with one of said axles, two gear members 20 loosely surrounding the first shaft, a second driven shaft, means for transmitting motion from said second shaft to one of said gear members, means comprising reversible ratchet mechanism for transmitting 25 motion from one of said gear members to the other of said members, and clutch mechanism located between said gear members for engaging either of said members to compel rotation of said first shaft, substantially 30 as described.

14. In a machine of the nature described, the combination of cutting mechanism and a truck supporting the cutting mechanism, the truck comprising carrying wheels, axles 35 on which said carrying wheels are mounted, a first shaft, gearing connecting said shaft with one of said axles, a second shaft, means for transmitting motion from said second shaft to one of the gear members, a third shaft, means for transmitting motion from the second shaft to the third shaft, a fourth shaft, reversible means for transmitting motion from the third shaft to the fourth shaft, means for transmitting motion from 40 the fourth shaft to the second of said gear members, and clutch mechanism for engaging either of said gear members to compel rotation of the first shaft, substantially as described.

15. In a machine of the nature described, the combination of cutting mechanism and a truck supporting the cutting mechanism, the truck comprising carrying wheels, axles 45 on which said carrying wheels are mounted, an upright first shaft, gearing connecting said shaft with one of said axles, a second shaft, and operator-controlled gearing comprising reversible ratchet mechanism between the second shaft and the first shaft for transmitting motion from the second shaft to the first shaft at different velocities, substantially as described.

16. In a machine of the nature described, the combination of cutting mechanism and a truck supporting the cutting mechanism, the truck comprising carrying wheels, axles 65 on which said carrying wheels are mounted, a first shaft, gearing connecting said shaft to one of said axles, a gear member loosely surrounding said shaft, a second shaft, means comprising ratchet mechanism between said second shaft and said gear member for constantly rotating the latter, a second gear member also surrounding the first shaft for rotation thereon, means between 70 the first gear member and the second gear member for transmitting motion from the first gear member to the second gear member in either direction, and clutch mechanism on the first shaft for engaging either 75 of said clutch members to compel rotation of said shaft, substantially as described.

17. In a machine of the nature described, the combination of cutting mechanism and a truck supporting the cutting mechanism, 85 the truck comprising carrying wheels, axles on which said carrying wheels are mounted, a first shaft, gearing connecting said shaft with one of said axles, two gear members 90 loosely surrounding the first shaft, a second driven shaft, means for transmitting motion from the second shaft to one of said members, means comprising reversible ratchet mechanism and worm gearing for transmitting motion from one of said gear 95 members to the other of said members, and clutch mechanism located between said members for engaging either of said members to compel rotation of said first shaft, substantially 100 as described.

18. In a machine of the nature described, the combination of cutting mechanism and a truck supporting the cutting mechanism, the truck comprising carrying wheels, axles on which said carrying wheels are mounted, a first shaft, gearing connecting said shaft with one of said axles, a main transmission shaft, a neck shaft connected with the main transmission shaft for rotation with the latter, two gear members loosely surrounding 105 the first shaft, means for transmitting motion from the main transmission shaft to one of said gear members, means for transmitting motion from one of said gear members to the other of said gear members at a different velocity and in either direction, and clutch mechanism for engaging either 110 of said gear members to compel rotation of said first shaft, substantially as described.

In testimony whereof I have signed my name this 27th day of May, in the year one thousand nine hundred and nineteen.

CYRUS S. OLDROYD.
